[57] CLAIM

The ornamental design for a shirt bin display unit, as
shown and described.

DESCRIPTION

FIG. 1 is a perspective view of a shirt bin display unit,
showing my new design;

FIG. 2 is a front elevational view thereof;

FIG. 3 is a rear elevational view thereof;

FIG. 4 is a right side elevational view thereof;

FIG. 5 is a top plan view thereof; and

FIG. 6 is a bottom plan view thereof.

*FIG. 1**FIG. 2**FIG. 3**FIG. 4**FIG. 5**FIG. 6*
